UNITED STATES PATENT OFFICE.

HENRY EDWARD TURPIN, OF OAKLAND, CALIFORNIA.

HEAD PROTECTOR.

Application filed November 15, 1921. Serial No. 515,241.

To all whom it may concern:

Be it known that I, HENRY E. TURPIN, a citizen of the United States, and a resident of Oakland, in the county of Alameda and State of California, have invented a new and Improved Head Protector, of which the following is a full, clear, and exact description.

This invention relates to improvements in head protectors, the broad object of the invention being to provide a resilient protecting device concealed within a hat to protect the head of a wearer from sudden blows.

15 A further object is to provide a protecting device of this character, which will be light in weight, automatic in operation, simple and practical in construction, durable and efficient in use, and one which will not interfere with the appearance of a hat.

With these and other objects in view, the invention consists in certain novel features of construction and combinations and arrangements of parts as will be more fully 25 hereinafter described and pointed out in the claims.

In the accompanying drawings:

Figure 1 is a view in longitudinal section through a cap showing my improved protecting device in place; and

Figure 2 is a bottom plan view of the cap with parts broken away and in section for clearness.

Referring in detail to the drawings, 1 35 represents a conventional type of man's cap, which includes a body 2 and a visor 3. The invention in this case resides in the provision of pneumatic or resilient means concealed within the cap for protecting the head of a wearer. It will be noted that in the particular form of the device shown, no sweatband is provided in the cap and instead of the sweatband I have substituted a length of perforated rubber tubing 4, 40 which occupies the position normally occupied by a sweatband and which is secured to the body of the cap in any approved manner.

It will be noted that the tubing 4 is formed 50 with diametrically opposed series of perforations 5 and 6 and that perforations 7, provided in the body of the cap register with the perforations 5 for a purpose which will hereinafter appear. A cord 8 is located within the length of tubing 4 and is 55 knotted at the front of the cap, as indi-

cated at 9, in the space between the two adjacent ends of the tube 4. This tubing snugly fits the head of a wearer of the cap when the cap is donned, and an additional protecting device is provided in the form of another tube 10 secured to the crown of the body 2. This tube is likewise provided with perforations 11, certain of which register with perforations 12 in 60 the cap, and a cord 13 is provided within the tube 10. It will be noted that the tube 10 includes offset portions adjacent the front and rear of the cap, these offset portions being indicated in dotted lines in Figure 70 2, at 14. These offset portions are provided so that the tubing 10 at the front and rear of the cap will seat more securely upon the head of a wearer and will be in a position to more efficiently protect certain 75 important bones of the skull.

The operation of the device is as follows: The perforations in the tubes 4 and 10 operate as valves to expel the air from the tubes when they are compressed, while 80 the cords 8 and 13 prevent the complete closing of the tubes. Both of the tubes act as shock absorbers to lessen the effects of sudden impacts against the head of a wearer.

85 These caps are primarily intended for the use of motorists, but may be worn by anyone carrying on a dangerous occupation where there is a possibility of being struck upon the head. I have shown the invention 90 applied to a cap, but it might, however, be applied to various other forms of men's soft hats and women's toques. The particular manner in which the tubes are secured in a cap is immaterial to the invention and 95 the details of the cords or drawstrings might also be considerably varied.

It will be evident, therefore, that although I have illustrated one of the preferred embodiments of the invention, numerous slight 100 changes and alterations might be made in the general form and arrangement of the parts described without departing from the invention, and hence I do not wish to limit myself to the precise details set forth, but 105 shall consider myself at liberty to make such slight changes and alterations as fairly fall within the spirit and scope of the appended claims.

I claim:

110 1. A device of the character described, comprising a head covering having a series

2
of unobstructed openings therein, and a cushioning tube located within the head covering and having unobstructed openings therein registering with the openings in the head covering.

2. A device of the character described, comprising a head covering having unobstructed openings therein, a cushioning tube located in the head covering and having a series of aligned unobstructed openings in its opposite walls registering with the openings in the head covering.

3. A device of the character described, comprising a head covering having openings therein, an open ended tube of elastic

material fitting the head covering, a cord extending through the tube and secured together at its ends and permitting adjustment of the tube, said tube having unobstructed openings therein registering with the openings of the head covering.

4. A device of the character described, comprising a head covering, having a plurality of series of unobstructed openings therein, a plurality of flexible tubes secured in the head covering and having aligned unobstructed openings registering with the openings in the head covering.

HENRY EDWARD TURPIN.
